UNITED STATES PATENT OFFICE.

BERTHA WESTBROOK REID, OF HIGHLANDS, NEW JERSEY.

DESIGN FOR A HANDKERCHIEF.

49,621.

Specification for Design.

Patented Sept. 5, 1916.

Application filed June 3, 1916. Serial No. 101,613. Term of patent 7 years.

To all whom it may concern:

Be it known that I, BERTHA WESTBROOK REID, a citizen of the United States, residing at Highlands, in the county of Monmouth and State of New Jersey, have invented a new, original, and ornamental Design for a Handkerchief, of which the following is a specification, reference being had to the accompanying drawing, forming a part thereof.

The figure is a face view of a handkerchief showing my new design.

I claim:

The ornamental design for a handkerchief as shown.

BERTHA WESTBROOK REID.

Witnesses:

GEORGE H. EMSLIE,
THEO. G. HOSTER.
